UNITED STATES PATENT OFFICE

GUSTAF EMIL JONSSON, OF HALMSTAD, SWEDEN

PULSATATOR FOR MILKING MACHINES AND THE LIKE

Application filed February 1, 1929. Serial No. 336,769.

The present invention relates to pulsators for use in connection with apparatus driven by a fluid pressure difference, for instance milking-machines driven by means of vacuum, whereby the pressure difference needed for the continuous operation of the machine is established between said vacuum and the atmospheric pressure. It is to be understood, however, that the invention is not limited to pulsators of this kind, and any pressure difference whatever may be used for the actuation of the same.

The main object of the invention is to provide for an effective shutting off of the higher pressure by means of the valve members forming a part of the pulsator and generally to increase the reliability of function by simpler means of construction, whereby the reversal of the valves is performed by the intermediary of a spring pressure acting alternately on both of the valves throughout the whole closing periods of the same.

The invention is illustrated in the accompanying drawings, wherein:—

Fig. 1 shows the pulsator seen from above after removal of the top closing cap.

Figs. 2 and 3 are sectional views at the lines II—II and III—III in Fig. 1 respectively.

Fig. 4, in the same section as Fig. 2, shows a modified embodiment of invention and the mounting of the apparatus on the lid of a milk can, and

Fig. 5 shows a top plan view of Fig. 4 drawn to a somewhat smaller scale.

Referring to the Figures 1—3 the pulsator consists of a housing 1 provided with a removable bottom cover or base plate 2. Internally the housing 1 is provided with two parallel and vertical valve chambers 3, each of which encloses a valve member 4 affixed to a valve spindle 5. The valve members in a suitable manner are constructed so as to act by both of their opposite faces for alternately closing of two different ports as described in the following.

Each of the valve chambers 3 is provided with a high pressure inlet 6 forming a seat for the upper side of the corresponding valve member, and a low pressure outlet 7 form-

ing a seat for the under side of said valve member. The high pressure inlets 6 stand in permanent communication with the atmosphere, or generally with the source of higher pressure, whereby the top closing cap 8 is provided with a suitable number of holes 9 for such purpose, and the low pressure outlets 7 by means of suitable bores stand in permanent communication with the source of low pressure, which in this instance can be considered consisting of a vacuum pipe 10 (compare especially Fig. 3). At a level between the high pressure inlet and the low pressure outlet each of the valve chambers 3 by means of suitable channels (as indicated in dotted lines in Fig. 1) stands in connection with a piping 11, 11 leading to the machine to be driven, and in case of milking-machines said pipings 11 are connected with the teat cups.

The constructional parts described above are previously known and form themselves no characteristical feature of the invention.

It is the main object of the invention to provide for a resilient closing pressure, which acts upon the valve members throughout the closing periods of the same, and it will be understood from the following that said closing pressure is gradually increased up to that moment in which the instantaneous reversal of the valve members takes place.

Each of the valve spindles 5 is hingedly connected with a crank lever 12, and the two crank levers concerned are affixed to, or carried out in one piece with, a sleeve-shaped member 13 supported by a bearing pin 14. The crank levers extend towards opposite sides relatively to the bearing pin, and consequently one valve member will move upwardly for closing the corresponding high pressure inlet when the other moves down for closing the low pressure outlet, and vice versa.

At the lower end, the housing 1 is provided with a diaphragm, the edges of which are preferably secured by means of the base plate 2, which by means of a suitable screw connection (not shown) is affixed to the under side of the housing. At the sides facing each other, the housing 1 and the base plate 2 are

provided with opposite recesses together forming a diaphragm chamber 16, which by means of the diaphragm is divided in two parts. The chamber part at hand above the diaphragm stands in communication with the atmosphere, and the chamber part below the diaphragm by means of a channel 17 (Fig. 2) stands in communication with one of the valve chambers 3.

10 The diaphragm 15 is connected with an upwardly extending guiding spindle 18 guided in a corresponding bore within the housing 1, and the under side of the diaphragm is acted upon in an upward direction by means 15 of a spring 19. Further the diaphragm, suitably by the intermediary of the spindle 18, is connected with a downwardly extending piston rod 20, the lower end of which carries a dash-pot piston 21 reciprocably mounted 20 within a corresponding cylinder 22 formed within the base plate 2 and closed by means of a suitable cover 23. The upper end of the cylinder 22 is also provided with a bottom serving as an abutment for limiting the travel 25 of the dash-pot piston in an upward direction, an adjustment of the amount of travel in that direction being provided for in such a manner that the piston rod 20 is carried out in the form of a screw which may, more or less, be screwed into a corresponding threaded bore in the spindle 18. The spindle 18 is connected to the centre of the diaphragm by means of flanges and a nut for pressing such flanges together in a manner easily understood from Fig. 2.

10 The spindle 18 is connected with an up-standing leaf spring 24, the upper free end of which is provided with a triangular head 25, which by means of the spring action is permanently pressed towards the central axis of the apparatus, i. e. towards the bearing pin 14. One edge of said head is facing inwardly and positioned in the path of movement of a roll 26 or the like antifriction device 45 supported by a suitable bearing pin affixed to the adjacent crank lever 12, so as to be raised or lowered at the tilting motion of the said crank lever during the reversal of the valve members, i. e. during the operation 50 of the apparatus.

10 It will be understood from the description above that the spring 24 tending to press the head 25 inwardly, due to the triangular shape of said head, will also tend to press the roll 26 downwardly in the position of the parts shown in Fig. 2, and after reversal of the valve members the opposite face of the head 25 will tend to press the roll 26 upwardly in the same manner. This upward and 55 downward pressure on the roll 26 will cause a corresponding pressure on the valve members against their seats, and it will be understood that this closing pressure acting upon the valves will be increased towards the moment of reversal, since the head 26 moves up

and down together with the diaphragm and thereby the head is pressed outwardly on account of contact against the roll 26, the reversal taking place just when the working edge of the head passes the extreme outer 70 generatrix of the roll.

The manner of action is as follows:—

When assuming that the constructional parts are in the position shown in Figs. 2 and 3, the vacuum at hand in the pipe 10 by means 75 of the right hand valve 4 in Fig. 3 (same as the valve shown in Fig. 2) is transmitted to the corresponding pipe 11, the other pipe 11 by means of the other valve being in communication with the atmosphere. By the 80 channel 17 the right hand valve chamber is also in communication with the space beneath the diaphragm 15, and therefore a vacuum is also created in said space. Consequently the diaphragm moves down, and when the working edge of the head 25 passes the outer generatrix of the roll 26 the crank levers 12 are instantaneously tilted into a reverse position due to the action of the spring 24, so that the valves 4 are reversed. Then the right hand 85 valve closes towards the vacuum pipe and opens to the atmosphere, and thereby the atmospheric pressure by means of the channel 17 is introduced into the space beneath the diaphragm, simultaneously as the pressure 90 conditions within the pipes 11 are reversed. When admitting the atmospheric pressure beneath the diaphragm, the spring 19 moves the same upwardly, and thereby the head 25 is also raised until it passes the outer generatrix of the roll 26 again, at which point another reversal of the valves takes place, and 95 so on.

As to the dash-pot mechanism described, the main object of the same is to prevent the 100 apparatus from "rushing", or in other words to obtain too great a frequency of pulsations. It has been found in practice, that the known pulsators are not quite safe in that respect, and in many instances a rather small 105 variation of the pressures employed, i. e. an increase of the vacuum, will cause the "rushing" of the pulsator. Especially in combination with milking-machines, such "rushing" of the pulsator has a very 110 dangerous and injurious effect on the udders of the cows and must positively be prevented. 115

On the other hand the dash-pot has for its secondary object to make it possible, if desired, to vary the frequency of the pulsations. 120 As far as milking-machines are concerned, the frequency need generally not to be varied, when once adjusted, but the pulsator according to the invention is not limited to the use in combination with milking machines only, as hinted at above, and in other combinations the possibility of variation may be useful. Then, the variation may be performed in the usual manner by enlarging or diminishing the free open area of the chan- 125 130

nel means interconnecting the cylinder chambers at opposite sides of the dash-pot piston. The means used for such purpose are well known in the art and need no description in this connection.

Finally it is also to be understood, that the retarding effect of the dash-pot will have no influence on the instantaneous reversal of the valve positions, and it can neither relieve 10 the closing pressure transmitted to the valves from the spring 24.

In the embodiment of invention shown in Figs. 4 and 5, the same reference letters are used on corresponding parts of construction.

15 The construction of the apparatus itself is substantially the same as described above, but a difference is to be found therein that the channel 17 in the housing 1 communicates with an annular groove 17^a provided in the 20 base plate and connected with the space below the diaphragm 15 by means of one or more radial bores 17^b.

The main difference is that the parts of the apparatus are not screwed together but 25 simply placed in contact with each other, whereby they are pressed together by means of a spring washer abutting against the handle of the milk can lid on which the apparatus is mounted.

30 In the drawing the can lid is marked A and provided with a handle B forming inwardly directed abutments B¹. The central portion of the lid proper is provided with a cup-shaped recess A¹ of such a cross sectional 35 shape that the bottom end of the pulsator can be inserted therein. The bottom end of the dash-pot cylinder 22 is open, and the part A¹ forms a container around the same, which container is in permanent communication with the cylinder 22.

When mounting the apparatus on the can lid, the recess therein is partly filled with a dash-pot fluid, which in this instance preferably consists of water. The parts of the apparatus, i. e. the base plate, the housing and the top closing cap, are placed in contact with each other, whereafter the whole assembly is inserted in the recess A¹, and it is to be noted that said recess is of such a depth that the 50 lower end of the housing is partly submerged therein. Thereafter the spring washer C is placed on the top closing cap, for which purpose the washer is preferably provided with a hole surrounding an upstanding portion of said cap, and the position at first assumed by the washer is in an angle to that shown in Fig. 5. Thereafter the washer is turned, so that the ends of the same enter below the abutments B¹, and for ensuring a rigid connection the ends of the spring washer C are somewhat recessed as shown at C¹, so that the washer cannot by inadvertency be turned loose again. Other securing means may, of course, also be used, but the resiliency of the 65 washer is sufficient in most cases. A packing

is suitably interposed between the under side of the base plate and a corresponding offset portion of the recess A¹, as shown in Fig. 4.

It will easily be understood, that by the means just described the apparatus may easily 70 be mounted and dismounted, and after dismounting, the parts of the same may be laid apart for the purpose of adjustment and inspection. The dash-pot fluid will not be removed simultaneously with the apparatus, and it remains in the recess A¹, wherein it 75 may be renewed if desired. Since the dash-pot fluid is thus laid open at the dismounting of the apparatus, it may preferably consist of clean water, so as not to add any impurities to the milk in case it should come in contact with the latter. The dash-pot fluid in the embodiment according to Figs. 2 and 3 need not be of such a kind and may consist of an oil, as usual.

What I claim and desire to secure by Letters Patent is:

1. In a pulsator of the character described, two valve members positioned in separate valve chambers provided each with a high pressure inlet and a low pressure outlet and adapted alternately to close said inlet and outlet respectively, interconnection means between the valve members and controlling them so that they take a reverse position in 90 their chambers, a diaphragm subjected at one side to the lower pressure, spring means acting upon the diaphragm in opposition to the higher pressure, means for intermittently subjecting the opposite side of the diaphragm to the lower pressure, a leaf spring connected with the diaphragm, a triangular head carried by the free end of said leaf spring, an antifriction means connected with the inter-connection means between the 95 valves and positioned in the path of movement of the said triangular head, and dash-pot means connected with the diaphragm and adapted for controlling the action of the leaf 100 spring causing the reversal of the valves by 105 the intermediary of said antifriction means.

2. In a pulsator of the character described, a housing for supporting substantially all of the movable members of the pulsation mechanism, a top closing cap positioned at the upper end of the housing and provided with means for establishing a permanent communication between the atmosphere and the interior of said housing, a base plate positioned at the lower end of the housing and forming an air tight cover thereon, a can lid provided with an exterior recess for taking up the lower part of the pulsator, a handle affixed to said can lid and provided with abutments, and a spring washer means adapted by its central portion to press on the top closing cap when the ends of the washer are placed in contact with said abutments.

3. In a pulsator of the character described, a housing supporting substantially all of the 115

movable members of the pulsation mechanism, a perforated top closing cap positioned at the upper end of said housing, a base plate positioned at the lower end of the housing and forming an air tight cover thereon, a dash-pot cylinder provided in said base plate and open to the lower face of the same, a dash-pot piston reciprocably mounted within said cylinder and connected with the movable members of the pulsation mechanism, a diaphragm secured at the edges between the housing and the base plate and connected with means for causing a reversal of the valves of the apparatus, a cam lid provided with an exterior recess for taking up the lower part of the pulsator in a manner so that the lower end of the dash-pot cylinder is in communication with the cavity within said recess, a handle affixed to said can lid and provided with abutments, and a spring washer means adapted by its central portion to press on the top closing cap when the ends of the washer are placed in contact with said abutments.

4. In a pulsator of the character described, a housing supporting substantially all of the movable members of the pulsation mechanism, a perforated top closing cap freely resting on the upper end of said housing, a base plate placed freely in contact with the under side of the housing without being secured thereto, a dash-pot cylinder provided in said base plate and adapted for coaction with a dash-pot piston connected with the movable members of the apparatus, a diaphragm positioned between the housing and the base plate and connected with means for causing the reversal of the valves of the pulsator, a can lid provided with an exterior recess for taking up the base plate and a portion of the lower end of the housing, a handle affixed to said can lid and provided with abutments, and a spring washer means adapted by its central portion to press on the top closing cap when the ends of the washer are placed in contact with said abutments.

5. In a pulsator of the character described, a valve housing, two valve chambers in said housing, each provided with a high pressure inlet and a low pressure outlet, a valve member in each chamber reciprocably mounted between the high pressure inlet and low pressure outlet therein and adapted alternately for closing either of them, mechanical interconnection means between the valve members adapted for positively controlling said valve members so that they take a reverse position in their chambers, a diaphragm subjected at one side to the higher pressure, spring means acting upon the diaphragm in opposition to said pressure, means for intermittently subjecting the opposite side of the diaphragm to the lower pressure, spring means actuated by the diaphragm for causing a sudden reversal of the valve positions, such spring

means being also adapted to exert a closing pressure on both of the valves when they are changed over into the position for closing the high pressure inlet, and means for preventing the valves from taking an intermediate position.

6. In a pulsator according to claim 5, dash-pot means connected with the diaphragm and adapted to control the action of the spring means for causing the sudden reversal of the valves.
